CLEANER HEAD

A Byrl Cox, Los Angeles, Calif.

Application May 26, 1933, Serial No. 672,913

1 Claim. (Cl. 15—104.13)

This invention relates to a cleaner head of the type used for cleaning the tubes or flues of steam boilers, oil stills or the like.

An object of this invention is to provide a cleaning head which is simple in design, which may be readily assembled and disassembled.

A further object is to provide the cleaning head with a plurality of floating cutter pins operatively mounted in suitable slots formed in the head and retained in operative position at one end by providing the first of each series of cutters with a flange or other similar means projecting into the pin bores thereof to prevent outward displacement of the cutter pins and by providing the coupling member with a flange or other suitable means for preventing rearward displacement of the cutter pins.

A further object is to provide a cutter head which may be completely disassembled by the removing of the coupling member.

A further object is to provide a cutter head which will be simple in design, rugged in construction and inexpensive of manufacture.

Other objects and advantages of the invention will become apparent as the nature of the same is more fully understood from the following description and accompanying drawing, wherein is set forth what is now considered to be a preferred embodiment. It should be understood, however, that this particular embodiment of the invention is chosen principally for the purpose of exemplification, and that variations therefrom in details of construction or arrangement of the parts may accordingly be effected and yet remain within the spirit and scope of the invention as the same is set forth in the appended claim.

In the drawing:

Figure 1 illustrates a top plan view of the cleaner head of this invention;

Figure 2 illustrates a sectional view taken substantially in the plane of line 2—2 of Figure 1;

Figure 3 illustrates a sectional view taken substantially in the plane of line 3—3 of Fig. 2; and

Figure 4 illustrates a side elevational view of the cleaner head.

In the preferred embodiment of the invention as illustrated in Figures 1 to 4, inclusive, the cleaner head may include a suitably shaped, more or less hollow body member 10 having a plurality of spaced flanges, as for example, a first or forward flange 11 a second or middle flange 12 and a third or rear flange 13. The first flange may be smaller in diameter than the two other flanges in order to provide the tool with a tapered nose.

The second flange 12 may be provided with any suitable number of slots 14, preferably three in number. Each of the slots 14 may be of equal size and equally spaced with relation to each other and from the axial center line of the cleaner head.

The third flange 13 may be provided with a corresponding number of slots 15 positioned directly below the slots 14 of the second flange.

There may be three sets of cutter assemblies 10 mounted in the cleaner head and as all of the cutter assemblies are of substantially the same construction one only will be described. A cutter pin 16 may be mounted so as to extend relatively loosely through a corresponding pair of slots 14—15 so as to be capable of freely sliding back and forth within the limits of these slots. But before the pin 16 is positioned in the slots a first cutter 17, which may be provided with a bore 18 of suitable size, may be positioned between the first and second flanges with the bore 18 directly registering with slot 14 and then a group of any suitable number of cutters 19, in this instance three, may be positioned between the second and third flanges with bores 20 thereof more or less in registration with the slots 14—15. Next the cutter pin 16 may be slid into the position as illustrated in Figure 2 so as to pass through slot 15, the bores 20 of the three cutters 19 and into the bore 18 of cutter 17. Means may be provided for preventing the pin from dropping or moving rearwardly out of position, which means may include providing the body member 10 with a threaded boss 21 and screw threading thereon a coupling means 22 having a flanged portion 23 of sufficient diameter to substantially cover slot 15 and to thus be in position to be engaged by pin 16 to prevent further rearward movement of the pin. In the preferred embodiment of the invention, as illustrated in Figures 1 and 2, the bore 18 of the first cutter may be provided with an inwardly projecting flange 23a to prevent a forward movement of the cutter pin while the cutter in turn is prevented from moving forward further than the inner surface of the first flange, due to the direct engagement of the cutter therewith.

Thus, it should be appreciated that after all of the cutters and pins have been properly positioned that it is only necessary to screw the coupling 22 into its operating position to complete the assembly of the tool and to provide thereby a simple and effective means for locking the pins and thereby the cutters in their operative positions. It is to be understood that the coupling 22 engages the under face of flange 13 before the pins have reached the full 55

extent of their possible travel so as to allow the pins sufficient looseness for freely sliding back and forth in slots 14 and 15, as the case requires.

If desired, the first cutters 17 may be somewhat tapered and provided with teeth 24 while the cutters 19 may be provided with teeth 25.

In operation the tool may be assembled as described and by means of the coupling member 22 connected to the usual driving shaft of a common form of flue cleaning apparatus, which need not be described here. The flue cleaning apparatus may next be set into operation, thus causing a very rapid rotation of the cleaning head, which now by means of the driving shaft may be passed through one tube after another of a boiler or still to remove carbon, lime or other deposits encrusted therein. The rapidly revolving cutters, due to centrifugal force, are forced to travel radially in the slots until the cutters roll around the inner surface of the flue and in the well known manner remove the deposits encrusted thereon.

Having fully described the invention, it is to be understood that it is not to be limited to the

details herein set forth, but the invention is of the full scope of the appended claim.

I claim:

A rotatable cleaner head including a body member having three spaced radially extending flanges, the foremost of said flanges being of smaller diameter than the diameter of the other of said flanges, the middle one of said flanges having a plurality of radially extending slots, the rearmost of said flanges having a like number of radially extending slots arranged in substantial alignment with the slots of the middle flange to form a plurality of sets of substantially aligned slots, a pin means for each set of said slots, a cutter means rotatably mounted upon the forward end of each of said pins and retained in operative position by the foremost of said flanges, each of said cutters having means for limiting the forward motion of its respective pin means, other cutter means rotatably mounted upon each of said pins between the middle and rear flanges, and a coupling means mounted upon the body and having means for limiting the rearward motion of said pins.

A BYRL COX.
